Primary Examiner — Eric L Goodman*Assistant Examiner* — Amy C Wierenga(74) *Attorney, Agent, or Firm* — Michael E. Dockins;
Shumaker, Loop & Kendrick, LLP**CLAIM**

The ornamental design for a release tool, as shown and described.

DESCRIPTION

FIG. 1 is a front perspective view of a release tool showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear perspective view thereof.

(Continued)

The broken lines shown in the drawings depict portions of the release tool that form no part of the claim.
